UNITED STATES PATENT OFFICE

HARRY S. VINCENT, OF RIDGEWOOD, NEW JERSEY, ASSIGNOR TO FRANKLIN RAILWAY SUPPLY COMPANY, OF NEW YORK, N. Y., A CORPORATION OF DELAWARE

LOCOMOTIVE

Application filed December 29, 1927. Serial No. 243,261.

This invention relates to locomotives and more particularly to articulated locomotives of either the single expansion or the compound type.

5 By my invention I aim to reduce the overhang of the boiler of such a locomotive, and to maintain the center of gravity of the boiler more nearly over the center of the wheel base longitudinally of the locomotive and also 10 more nearly over the center of the wheel base transversely of the locomotive when it is taking curves.

Another object of the invention is the reduction of the length of the steam connections to the various operating cylinders.

A still further object of the invention contemplates reducing the size of certain of the steam connections, particularly those which must be provided with universal or flexible 20 joints, and thereby permit such joints to be of smaller dimensions and consequently more readily packed and maintained tight.

The invention contemplates further the accomplishment of the foregoing objects by the 25 employment of a novel frame and driving wheel construction which makes possible the above and other advantages.

How the foregoing together with other objects and advantages are obtained will be 30 clear from a consideration of the following description and the accompanying drawing.

In the drawing, Figs. 1a and 1b placed together at their lines $x-x$ form a somewhat diagrammatic side elevation of a locomotive 35 embodying my improvements.

Referring now particularly to the drawing, the locomotive boiler is indicated by the reference numeral 2. This boiler, it will be seen, is mounted above two frames, the forward of which is indicated at 3, and the other at 4. These two frames are articulated together by the connection indicated at 5 and the forward frame is provided with bearer means 6 for the locomotive boiler which permit lateral movement relative thereto. The 45 boiler 2 is, of course, rigidly secured to the rear frame member 4.

A cylinder 7 is provided on each side of the locomotive for driving the set of wheels 8 in the rear group and these cylinders are

rigidly secured to the boiler 2 and the rear frame 4. A set of cylinders 9 are secured to the movable frame 3 and serve to drive the wheels 10 of the forward group. The steam connections are arranged in such manner that both of the pairs of cylinders are supplied with live steam. They receive their supply from the dry pipe 11 and the cylinders 7 exhaust thru the pipe 12. A pipe 13 communicates with the steam chest of cylinder 7 and serves to carry steam from the cylinders 7 forwardly to the cylinders 9. Exhaust pipes 14 are also provided for the cylinders 9. These connections 13 and 14 to the cylinders on the movable frame 3 are provided with flexible connections 18 at their ends.

If desired the two pairs of cylinders may be compounded.

A booster motor 15 may be applied to the trailing truck 16 as shown in the drawing, 50 or it may be applied to the pilot truck 17 or, if desired, such motors may be applied to both the pilot and trailing trucks.

It is to be noted that the driving wheel axles are divided into two groups, one of 55 which includes more than the other. In the particular example illustrated there are six driving wheel axles in the rear frame member and two in the forward frame. In view of this uneven division of the driving-wheel axles 60 and in view of the fact that the boiler is rigidly secured to the frame carrying the larger group there will be a relatively small boiler overhang. This arrangement also brings all the cylinders nearer to the points on the locomotive boiler to which the live steam and exhaust pipes from the cylinders must lead (i. e. the dry pipe and the smoke box). Thus these steam connections are reduced in length and losses due to radiation are reduced to a minimum. Such an arrangement also permits the cylinders for the small and relatively movable group of drivers to be made of smaller dimensions as they are required to drive only 65 a relatively small group of wheels. Consequently the diameter of the steam connections to the cylinders 9 may be made relatively small and their flexible joints of corresponding dimensions and therefore very readily and effectively packed against leakage.

According to the foregoing I have provided a locomotive of the articulated type which materially and effectively reduces the boiler overhang as well as heat losses due to radiation and leakage of the steam connections.

I claim:—

1. In an articulated locomotive having a total of not less than eight pairs of main driving wheels, a main frame having six pairs of the main drivers mounted therein, and a supplemental frame articulated to the main frame and having other pairs of main drivers mounted therein, the number of pairs of drivers mounted in said supplemental frame being less than the number mounted in the main frame.

2. In an articulated locomotive having a total of eight pairs of main driving wheels, a main frame having six pairs of the main drivers mounted therein, and a supplemental frame articulated to the main frame and having the other two pairs of main drivers mounted therein.

3. In an articulated locomotive having a total of eight pairs of main driving wheels, a main frame having six pairs of the main drivers mounted therein, and a supplemental frame articulated to the main frame and having the other two pairs of main drivers mounted therein, together with a single expansion driving engine for each group of drivers including relatively large capacity cylinders for the larger group and relatively small capacity cylinders for the smaller group with relatively large and small size steam connections for the large and small cylinders, respectively.

4. In an articulated locomotive having a total of eight pairs of main driving wheels, a main frame having six pairs of the main drivers mounted therein, and a supplemental frame articulated to the main frame and having the other two pairs of main drivers mounted therein, together with a single expansion driving engine for each group of drivers including relatively large capacity cylinders for the larger group and relatively small capacity cylinders for the smaller group with relatively large and small size steam connections for the large and small cylinders, respectively, the supply connection for the small cylinders being extended between those of the two engines and communicating with the supply or inlet side of both the large and small capacity cylinders.

5. In a locomotive; a boiler; a main driving wheel frame structure extended along a major portion of the length of the boiler and with which the boiler is mounted to move; a shorter driving wheel frame structure articulated to the main frame structure; at least two pairs of main driving wheels mounted in the articulated frame structure; a number of main driving wheels, equal to at least

twice the number in the articulated frame, mounted in the main frame structure; a single set of relatively small cylinders for actuating the driving wheels in the articulated frame; a single set of relatively large cylinders for actuating the driving wheels in the main frame; a source of steam supply and a point of exhaust steam disposal located on the boiler between the two sets of cylinders; relatively large size but short steam connections extended between said source and said point of disposal and the relatively large cylinders; relatively small size and short steam supply and exhaust connections for said relatively small size cylinders; and correspondingly small flexible joints for the steam supply and exhaust connections last mentioned; whereby the boiler overhang and losses due to leakage and radiation from the various steam connections are maintained at a low value.

In testimony whereof I have hereunto signed my name.

HARRY S. VINCENT.
